(57) **CLAIM**

The ornamental design for an air chuck, as shown and described.

DESCRIPTION

FIG. 1 is a perspective view of the air chuck showing an attached handle and dual-head chuck;

FIG. 2 is a right side elevation view thereof;

FIG. 3 is a left side elevation view thereof;

FIG. 4 is a top plan view thereof;

FIG. 5 is a bottom plan view thereof;

FIG. 6 is a front elevation view thereof; and,

FIG. 7 is a rear elevation view thereof.

All broken lines illustrate portions of the air chuck that form no part of the claimed design.
